(57) **CLAIM**

The ornamental design for a storage rack for office equipment, as shown and described.

DESCRIPTION

1. Storage rack for office equipment

1.1 : Perspective

1.2 : Front

1.3 : Back

1.4 : Top

1.5 : Bottom

1.6 : Right

1.7 : Left

1.8 : Cross sectional

1.9 : Perspective

1.10 : Perspective

This article is a storage rack for office equipment that can be attached to a wall surface by magnets and has small circular holes on the front to which small containers can be attached; fig.1.1 is a perspective view of a rack showing the new design; fig.1.2 is a front view thereof; fig.1.3 is a back view thereof; fig.1.4 is a top view thereof; fig.1.5 is a bottom view thereof; fig.1.6 is the right view thereof; fig.1.7 is a left view thereof; fig.1.8 is a vertical cross-sectional view taken along the line 1.8-1.8 in fig.1.2; fig.1.9 is a perspective view in state wherein the door is open of fig.1.1; fig.1.10 is a perspective view with environmental structure shown with broken line that forms no part of the claimed design.
